UNITED STATES PATENT OFFICE.

ANDREW J. BAKER, OF TUCSON, ARIZONA.

CROSSING PROTECTOR.

Application filed March 27, 1923. Serial No. 628,097.

To all whom it may concern:

Be it known that I, ANDREW J. BAKER, a citizen of the United States, residing at Tucson, county of Pima, and State of Arizona, have invented certain new and useful improvements in Crossing Protectors; and I do hereby declare the following to be a full, clear, and exact description of the invention, such as will enable others skilled in the art 10 to which it appertains to make and use the same.

This invention relates generally to crossing protectors; and relates more particularly to automatic devices for preventing collisions at cross-roads by giving visible, audible or other signals and by placing barriers or gates across one of the roads on the approach of a vehicle to the crossing.

While these devices may be used to prevent collisions at the crossing of two or more highways, they are particularly adapted for use at the crossing of a railroad and a highway, the devices being operable on the approach of a train to the crossing. For 20 purposes of illustration, in this application the devices will be shown used at the crossing of a railroad and a highway, but it is to be understood that the invention is not limited to this particular use.

The crossing of a road, street or highway by a railroad at grade has long been recognized as a source of great danger and many casualties have resulted from collisions between trains and vehicles at such crossings.

When traffic is deemed sufficient to warrant it, railroads station signal men to guard grade crossings by giving signals or by operating gates to warn persons of the approach of a train. However, there are many crossings, especially in rural districts, where, 35 probably because of the expense which would be entailed, no protection whatever is afforded.

Devices have been proposed heretofore 45 which will operate automatically, and thus avoid the expense of a signalman or gate- man, to warn persons of the approach of a train to the crossing and to prevent crossing of the tracks until after the train has 50 passed. In order to be entirely successful, devices relating to this art must meet a number of somewhat exacting requirements. In the first place, a device of this kind should be capable of operating with any number 55 of tracks. It should also be operable irrespective of the direction in which the

trains run. Furthermore, such a device should operate in cases where the train comes to the crossing, stops, and then backs up out of the entering end. Such a device 60 should also be operable without interfering in any way with the operations of the automatic electric block signal systems with which most railroads are equipped today. In addition, a device of this kind should 65 also be reliable in operation and therefore of simple and strong construction and, while it should be positive in its operation and not easily interfered with or damaged, nevertheless, due allowance should be made 70 in case the gate mechanism comes in contact with a vehicle or pedestrian to avoid injury to the pedestrian and damage to the device or the vehicle. The importance of the last mentioned desideratum can be appreciated 75 when it is realized that these devices are operated mechanically and therefore it is possible for the gate to be operated before the highway is clear of the traffic.

An object of this invention is to provide 80 apparatus for protecting crossings operable with any number of railroad tracks and operable irrespective of the direction in which the trains run.

Another object of this invention is to provide 85 crossing protecting apparatus operable even in cases where the train comes up to the crossing, stops and then backs up out of the entering end.

A further object of the invention is to 90 provide apparatus for protecting crossings operable without interfering in any way with the normal or usual operation of an automatic electric block signal system.

Still another object of this invention is to 95 provide apparatus for protecting crossings set into operation by movements of a train, but with no part of the train coming in actual contact with any part of the protecting apparatus at any time.

Another object of this invention is to 100 provide apparatus for protecting crossings which cannot be tampered with or operated without authority and which cannot be damaged or rendered inoperative by snow, rain, sand, dirt, etc.

One more object of this invention is to 110 provide crossing protecting apparatus of simple and rugged construction operated by means which will yield to prevent injury or damage to the apparatus if any part thereof comes in contact with an obstruc-

tion which would prevent the apparatus from operating.

Other objects and advantages of the invention will be obvious from the following description taken in conjunction with the accompanying drawings which illustrate one specific embodiment of the invention, but it is to be understood that the specific embodiment of the invention illustrated and described is merely one form typical of the broad invention chosen to explain the principles of the broad invention and is to be taken as illustrative and not restrictive.

15 Referring to the drawings,

Fig. 1 is a diagrammatical plan view of an assembly of apparatus embodying the invention as used at a railway crossing;

20 Fig. 2 is a side view of one of the crossing protectors proper;

Fig. 3 is a plan view of one of the road-bed switches with the cover plate removed;

Fig. 4 is a sectional view on line 4—4 of Fig. 3, but with the cover plate in place;

25 Fig. 5 is a diagrammatical view of the apparatus carried by the train for setting the crossing protectors into operation;

Fig. 6 is a longitudinal sectional view of one of the crossing protectors, the upper part being cut off. For clarity, some of the parts have been shown partly in section and partly in elevation;

30 Fig. 7 is a view on line 7—7 of Fig. 6 looking in the direction of the arrows showing the underside of the lower gate arms support;

Fig. 8 is a view on line 8—8 of Fig. 6, looking in the direction of the arrows, showing the ratchet mechanism;

40 Fig. 9 is an enlarged fragmentary view in section of the clutch or over-running connection in the gearing for the bell ringing and governor operating mechanism;

45 Fig. 10 is an enlarged detail view in elevation of a part of the gate latch releasing and circuit breaker operating mechanism;

50 Fig. 11 is a diagrammatical view of the electrical mechanism and wiring of one of the crossing protectors; and

Fig. 12 is an enlarged sectional view taken on line 12—12 of Fig. 6 looking in the direction of the arrows to show the 55 bell ringing mechanism.

Broadly stated, the invention embodies a barrier or gate, means for yieldingly operating said gate, means for energizing said operating means, and means for controlling the operation of the energizing means.

60 Stated more specifically, the invention embodies a gate, spring means for operating said gate, means for locking said gate against operation, means for winding said

spring means, means controlled by movements of a vehicle for connecting said winding means with a source of power, and means for automatically disconnecting the winding means from the power source after a predetermined operation of said winding means and for releasing said gate locking means.

65 Referring to the drawings, Fig. 1 shows an assembly view of the apparatus as used at the crossing or junction of a single track railroad and a comparatively wide highway, but it will be obvious, especially as the description proceeds, that the crossing protectors can be used with any desired number

70 of tracks to protect a road or highway of any width. Accordingly, the invention is not to be limited to the particular arrangement illustrated which has been selected from many possible arrangements for convenience in describing the invention.

75 In Fig. 1, 10 designates a road or highway wide enough for two or more lines of traffic and 11 indicates the railroad track, 12 refers generally to the crossing protectors, two of which are shown, one on each side of the track. The operation of

80 the crossing protectors is controlled by a relay or relays, (not shown in this figure), located in a normally open electric circuit composed, in part, of conductors indicated generally by 13, 14, 15, 16, 17, and 18, the

85 circuit being closed by a switch or switches 19 actuated by means carried by the train, resulting in the crossing protectors 12 90 being set into operation. The wiring just

95 described may be arranged in underground conduits or laid along the ties. Part of the wiring, especially conductors 15 and 16, may be strung on poles, which usually

100 extend up and down the track on each side of the crossing for some distance, in which instance the apparatus is preferably protected from possible damage by lightning

105 by the use of lightning arresters shown at 20. The operation and control of the crossing protectors will be explained more in detail hereafter.

110 Referring to Figs. 1, 2 and 6, it will be seen that each crossing protector 12 comprises a casing or body 21 which rotatably

115 supports in upright position a shaft 22 carrying horizontally extending arms or spreaders 23 forming a gate member or barrier. As shown in Figs. 1 and 2, the

120 arms or spreaders 23 extend on opposite sides of rotatable shaft 22 and the body or casing 21 is placed at or near the center of the street or highway. This is a very desirable arrangement because when the

125 gate member is in open position (as shown in full lines in Fig. 1), it compels traffic along the street to divide into two definite lines or streams, thus avoiding the confusion or danger of collision which

would result if vehicles were not prevented from running in the center of the road or street. It is clear however, that, if desired, the crossing protectors can be placed at or 5 near the side of the road and, especially on a narrow street or highway, the arms or spreaders can extend from only one side of shaft 22. The arms or gate members may be of any suitable construction and arrangement, but the construction illustrated has been found especially desirable because it possesses lightness together with great strength. Each arm 23 comprises a main or lower arm member 23^a and a brace or upper arm member 23^b, the two oppositely extending arms being arranged in the form of a truss. The lower or main arm members 23^a are fastened by screw threads or other suitable means in sockets provided in a 10 block or casting 24 secured to shaft 22 just above the top of the casing 21. The brace or upper arm members 23^b are secured in a similar manner to a block or casting 25 secured to shaft 22 a short distance above 15 block 24. The upper and lower arm members are preferably made of pipe, the lower member being made of pipe arranged in sections graduated in diameter, the sections getting smaller toward the outer ends of 20 the arms, the last or outermost section being bent back on itself and then continued to form the brace or upper arm member. As shown in Fig. 1, the crossing protectors are set back from the track a sufficient distance 25 to allow vehicles, which might be caught between the two crossing protectors when they are operated to swing across the street, to stand between either of the crossing protectors and the track without being hit by 30 the train.

The mechanism for turning shaft 22 and arms 23 attached thereto is mounted or housed in the main casing or body 21 where it will not only be protected against the 35 elements, but will also be safe against tampering or meddling. Referring to Fig. 6, casing 21 is supported in an upright position in a foundation or base 26, which may be of any suitable construction, although 40 the foundation shown is made of concrete. The upper end of casing 21 is closed by a cap 27 which is provided centrally with a bearing 28 through which shaft 22 extends. The lower end or bottom of casing 21 is 45 closed by a plug or disk 29 in which is centrally mounted a thrust roller or ball bearing 30 which receives the reduced end 22^a of vertical gate shaft 22 whereby the latter is rotatably supported. Shaft 22 is prevented from moving longitudinally in one direction by thrust bearing 30 and longitudinal movement in the other direction is prevented by a collar 300 secured to shaft 22 so that it abuts the underside of cap 27. 50 Shaft 22 is also rotatably supported and

braced at a point intermediate bearings 28 and 30 by a disk or brace member 31 secured to the casing by any suitable fastening means and provided centrally with a bearing 32 through which shaft 22 extends. It will be 55 seen that, with the arms or gate in the position shown in full lines in Fig. 1, a quarter of a revolution of shaft 22 will bring the gate to the position shown in dotted lines in Fig. 1, in which position traffic across the 60 tracks will be cut off, while another quarter of a revolution of the gate shaft will again place the gate in the position which will allow traffic to pass along the street and over the tracks. In other words, each revolution 65 of shaft 22 through an arc of 90° from the open position (where traffic is permitted to pass) will successively close and open the gate.

Means are provided which will exert a 70 positive force to operate the gate, but which will yield, should the gate strike some obstacle which would prevent it from continuing to turn, thereby preventing injury or damage to the gate mechanism or to the 75 obstacle, which might be a pedestrian or vehicle. The yielding or resilient operating means, in the present instance, comprises spring means 33 and while the specific number and type of springs may differ, a single 80 coiled spring has been illustrated. The spring is coiled around shaft 22, one end of the spring being connected to a collar 34 secured to shaft 22, the other end of the 85 spring being connected to a ratchet wheel 100 or device 35 loosely or rotatably mounted on shaft 22. Ratchet wheel or disk 35 is prevented from rotating in one direction, that is, in the direction in which the spring would unwind, by a spring-pressed pawl 36 105 pivotally mounted on suitable supports 37 attached to the casing 21.

Means are provided for impressing or 110 storing energy in the yielding operating means so that the latter can operate the gate shaft 22. In the example shown this comprises an electric motor 38 secured or mounted on the exterior of casing 21. One end of the motor shaft 39 extends into casing 21 through an opening provided for this purpose, this end of the shaft terminating in a supporting bearing 40, provided in the interior of casing 21. The opposite end of motor shaft 39 extends 115 through a bearing provided in motor casing or housing 41. Shaft 39 extends from casing 41 a distance sufficient to support a hand crank device (to be explained later) indicated generally by 42. Rotation of motor shaft 39 is transmitted by a gear 43 and gears 44 and 45, fixedly secured to the countershaft 46 mounted for rotation in bearings 47, to a crown or bowl gear 48 secured to ratchet wheel or disk 35. It will 120 be seen that rotation of motor 38 will be 125

130

transmitted, through the gearing just described, to spring 33, winding the same or placing it under tension. This will tend to turn gate shaft 22 unless it is held against 5 rotation.

Means are provided for normally holding or locking gate shaft 22, and gate 23 carried thereby, against rotation. In the illustrative apparatus this means comprises a 10 latch or plunger 49 mounted for reciprocation in a bracket or support 50 attached to main casing or body 21 at or near the top thereof, a spring 51 pressing plunger 49 through an opening in cap 27 so that normally the plunger projects into one of four recesses or sockets 52 provided in the underside of block or lower arms casting 24 to hold said block and gate shaft 22 against rotation. Referring to Fig. 7, it will be seen that the four recesses or sockets 52 provided in the under face of block 24 are spaced 90° apart in a circle concentric with shaft 22, two of the recesses being in line with oppositely projecting arms 23 and the other two being placed in a line at right angles to this alignment. When spring 33 is wound, it tends to turn shaft 22 which is locked or prevented from turning by plunger 49 engaging in one of the recesses 52 in block 24. 30 When plunger 49 is withdrawn, shaft 22 and gate 23 carried thereby are rotated one fourth of a revolution, when plunger 49 will engage in the next recess 52 to prevent further rotation.

35 While, broadly speaking, any mechanism for operating plunger 49 to release gate shaft 22 may be provided, means have been provided for accomplishing this purpose operable by the winding mechanism and so arranged that after the winding mechanism has wound spring 33 one fourth of a turn, plunger 49 is operated to release the gate shaft, and spring 33 then turns the gate shaft one fourth of a revolution, when plunger 49 engages in the next recess 52 to stop the gate shaft from rotating. In the illustrative example, the specific mechanism for accomplishing this purpose comprises a trip or lever 53 pivotally supported by a bolt or bracket 54 attached to main casing 21. An arm or link 55 pivotally connects plunger 49 and bell crank lever 53 so that when the latter is caused to swing on its pivot 54, plunger 49 is withdrawn from a recess 52 against the 55 tension of spring 51. Link 55 is provided with a laterally projecting pin 55^a which will be described later. In order to trip or swing lever 53, bowl or crown gear 48 is provided with laterally projecting pins 56, 60 there being four of these pins mounted 90° apart and so arranged that just as a quarter revolution of bowl gear 48 is being completed (which would mean that the spring 33 had been wound one quarter of a turn), 65 one of the pins 56 projecting from the sides

of gear 48 will strike lever 53, reciprocating connecting link 55 and plunger 49 to release gate shaft 22, permitting it to turn until it is held again after a quarter revolution.

70 While an electric motor 38 for winding spring means 33 has been shown, it is obvious that motors operated by other sources of power may be used, although an electric motor is preferred because it can be easily controlled. For each quarter turn 75 or movement of the gate, electric motor 38 must be connected to a source of electrical energy and then disconnected from this source and means have been provided for accomplishing these operations automatically. 77 indicates a source of electrical energy which, in the example illustrated, comprises a storage battery. Storage battery 77 is housed in a casing 58 attached to main casing or body 21. One line of the 80 electric circuit between battery 77 and motor 38 comprises conductors 59 and 60 normally connected together by a switch 61. The other line of the circuit comprises conductors 62 and 63 separated by a gap adapted 85 to be closed by switch member or armature 64 (normally in open position) of an electromagnetic switch or relay 65. The electric circuit between electric motor 38 and battery 77, it will be observed, includes two 90 switches, one normally closed and the other normally open, so the motor circuit is normally open. When relay 65 is energized, the circuit between the motor and battery 95 is closed, so that motor 38 begins to wind 100 spring 33. It is the function of switch 61 to break or interrupt the motor circuit when motor 38 has completed its winding operation. Switch 61 comprises a pivoted member 105 mounted adjacent to link 55 of the gate locking and releasing mechanism and directly in the path of the pin 55^a projecting from one side of the reciprocable link 55. When link 55 is reciprocated, pin 55^a will engage switch member 61 causing it to swing 110 and break the motor circuit, stopping the motor. Switch member 61 is then returned by spring tension or any other suitable means to its original position. From the foregoing it will be observed that, as the 115 motor completes its winding operation, it is automatically stopped and the gate is then released and allowed to make a quarter turn.

120 While an electromagnetic switch or relay 65 for closing the motor circuit has been shown, it is obvious that a manually operable switch could be used, but an electromagnetic switch or relay is preferred because this can be controlled by movements 125 of a train. Relay 65 is compound wound that is, there are two separate and distinct coils of wires on the magnets. The terminals of one set of coils are marked *a*, and the terminals of the other set are marked 130 *b*.

Either of the two relay coils can operate the relay armature 64 independently of the other. For convenience in describing them, relay coil *a* will be termed the main relay coil and relay coil *b* will be called the auxiliary relay coil. Conductor 18 which forms a part of the main relay circuit, is connected to one terminal of main relay coil *a*, the other terminal being connected by conductor 66, normally closed switch 61, and conductor 59 to battery 57 to which conductor 17, also a part of the main relay circuit, is connected. Conductors 17 and 18 are connected by conductors 13, 15 and 14, 16 with roadbed switch 19, therefore, it follows (see Fig. 11) that when roadbed switch 19 is actuated by a train approaching the crossing to close the main relay circuit, main relay coil *a* is energized, moving armature 64 of relay 65 to close the circuit of motor 38. Roadbed switch 19, which will be described in detail later, is only closed for a movement by the train in passing, consequently, some means to hold relay armature 64 in the position bridging contacts 64^a and 64^b of the motor circuit must be provided, otherwise the motor would be operated only for an instant. An auxiliary coil *b*, heretofore referred to, has been provided on relay 65 which is energized at the time the motor circuit is closed to maintain the relay armature in a position bridging contacts 64^a and 64^b of the motor circuit. Auxiliary coil *b* is connected in shunt in the motor circuit, one terminal of the coil being connected by conductor 67 with conductor 62 forming a part of the motor circuit, the other terminal of the coil being connected by conductor 67^a to relay armature 64 which connects with contact 64^b to which conductor 63, also forming a part of the motor circuit, is connected. Auxiliary coil *b* therefore maintains armature 64 in closed position until switch 61 is actuated to break the motor circuit, at which time the motor is cut off and relay armature 64 is released.

It has been found desirable to provide means for controlling the speed at which the gate turns and also to provide means for giving audible and visible signals or indications of the approach of a train. 68 indicates generally a governor, which may be of any suitable type, mounted in the lower end of casing 21, the governor being connected by gears 69, 70, 71, 72, 73 and 74 with gate shaft 22, thereby controlling the speed at which gate shaft 22 turns. The governor illustrated, which is of a well known type, comprises two end blocks 75 and 76 mounted on governor shaft 77 rotatably supported in bearings 78. Block 75 is rigidly secured to shaft 77 while block 76 is mounted on shaft 77 so that rotation of block 76 relative to the shaft is prevented, but sliding of block 76 on shaft 77 is per-

mitted. Governor blocks 75 and 76 are connected by a plurality of springs 79, to each of which is secured a governor weight 80. Rotation of shaft 77 causes governor weights 80 to fly out, flexing springs 79 causing disk 70 rigidly attached to slideable governor block 76 to slide into engagement with and rub against regulating disk 82. Regulating disk 82 is mounted on a threaded shaft 83 secured to casing 21, disk 82 being held in 75 adjusted position on the shaft by lock nuts 84. By adjusting the position of regulating disk 82, the speed of the governor and in turn the speed of the gate shaft can be controlled and regulated.

Gear 70, which forms a part of the train of gearing operating the governor, actuates the gong-sounding mechanism which is mounted within casing 21 just above the governor. 85 indicates a gong fastened by 86 a bolt or other suitable securing means 86 to casing 21, the gong being sounded by a clapper 87 pivotally mounted intermediate its ends on a bracket or bolt 88 extending from casing 21. A link 89 pivotally connects bell clapper 87 with one arm of a crank 90 pivotally mounted on a bolt or bracket 91 extending from casing 21. The other arm of crank 90 is adapted to be engaged by the spokes of gear wheel 70; so 95 that gear wheel 70, in turning, causes crank 90 to oscillate, and this oscillation is transmitted by link 89 to clapper 87 which in turn strikes gong 85. Gear 70 is rigidly secured to counter-shaft 92 rotatably supported in 100 bearings 93. Gear 71, which meshes with gear 72, is also rigidly secured to counter-shaft 92.

The various parts comprising the speed control and governing mechanism and the operating gearing are quite heavy, so that when once started in motion, they cannot be suddenly stopped, as for instance, when rotation of the gate is stopped by plunger 49, without putting quite a strain on the 110 various parts which makes up this mechanism. I have provided means whereby the speed control and gong-sounding mechanism and the major part of the operating gearing are disconnected from the gate shaft 115 when turning of the latter is stopped, the speed control and gong-sounding mechanism and gearing continuing to turn until the force stored up in these turning parts has spent itself. This means, in the present example, takes the form of a clutch or ratchet connection between gears 72 and 73. Both these gears are carried by counter shaft 94 supported in bearings 95. Gear 72 is secured to a sleeve 96 rotatably mounted on shaft 94, gears 73 being secured to a second and adjoining sleeve 97 also rotatably mounted on shaft 94. Sleeves 96 and 97 are pressed together by a spring 98 mounted on the extending end of shaft 94, a cap or col. 120

125

130

lar 99 retaining the spring in place on the shaft. The adjoining ends of sleeves 96 and 97 are formed with ratchet or clutch teeth so arranged that rotation in one direction only will be transmitted from one sleeve to the other. It will be seen that, at the completion of a turning movement of the gate, when gate shaft 22, bowl gear 74, pinion 73 and sleeve 97 are stopped quite suddenly, 10 sleeve 96, gear 72 and the rest of the gearing and other mechanism for sounding an alarm and controlling the speed at which the gate turns need not stop, but can continue to rotate until the stored-up force is 15 spent.

In order to warn persons at night when the gate member is thrown across the highway, lamps 100 have been provided. These lamps are mounted on the arms or spreaders 23, the wires 101 carrying the current for the lamps being conducted through the hollow pipe of which each arm or spreader is constructed. Lamps 100 swing with the arms, so in order to maintain an electric 20 connection with the source of current, which remains stationary, contact rings 102 are provided in block or arm casting 24, wires 101 being connected with these contact rings which are, of course, suitably 25 insulated from each other and from the arm casting or block. Contact rings 102 are engaged by contacts or brushes 103 secured to cap 27. Contacts 103, which are insulated 30 from cap 27 and from each other, are connected by wires 104 with battery 57. If 35 rings 102 are concentric with gate shaft 22 so that brushes or contacts 103 always maintain contact therewith even while the gate is turning. A suitable switch (not shown) is 40 provided for cutting out the lamps. If desired, contact rings 103 may be interrupted or broken into segments, so that lamps 100 will only be lighted when the gates are across or partially across the highway, the broken or interrupted places of 45 the rings automatically breaking the circuit as the gate swings to open position.

The roadbed switch, to which general reference has already been made, by which 50 the operation of the protector can be controlled by the movements of a train, may be of any suitable type, but the type illustrated is especially desirable for several reasons. In the first place, the working 55 parts of a switch such as illustrated are entirely enclosed so that these parts are protected from damage by the elements and unauthorized operation of the switch is prevented. Probably the greatest advantage, 60 however, resides in the fact that the switch can be operated without any part of the train coming in contact therewith. The switch indicated generally by 19 comprises a plate or base 105 provided with an up- 65 standing annular projection or ring 106.

The casing formed by base or plate 105 as a bottom and ring projection 106 as the side walls is closed by a cap 107 made of brass or other non-magnetic material connected by any suitable means, such as screw 70 threads, to ring 106. In the example, illustrated, recessed cap 107 is interiorly screw threaded to screw on threads provided on the exterior of ring 106, the cap screwing down against a washer or gasket 108 on base 105 to provide a water-tight connection. Mounted on base 105 within ring 106 is a bracket 109 pivotally supporting a lever 110 made of steel or other magnetic material. One end 110^a of lever 110 is flattened like a paddle while the other end 110^b supports an adjustable balance weight 111 made of brass or other non-magnetic material. A contact 112 is secured to the interior wall of ring 106 in the path or swing 85 of lever 110. Balance weight 111 is so adjusted on arm 110^b of lever 110 that the paddle end 110^a of the lever slightly overbalances or tips the lever, the paddle end of the lever in this position being just 90 slightly below, and out of contact with, contact 112. It should be noted that bracket 109 and contact 112 are both insulated from their respective supports. Conductors 13 and 14 of the relay circuit 95 are connected, respectively, to contact 112 and bracket 109 so that when lever 110 contacts with contact 112 the relay circuit is closed which in turn closes the motor circuit and the protector is operated. 100

The roadbed switch is operated by magnetic means carried by the train without any part of the train coming in contact with the switch. Referring to Fig. 5, 113 indicates diagrammatically the engineer's cab of a locomotive and 114 shows diagrammatically part of the lower frame work of a locomotive tender. 115 indicates an electromagnet secured by bracket 116 to the underside of the framework of the locomotive tender, magnet 115 being supported as near the ground as practicable. Electromagnet 115 receives current from a battery or other source of current 117 through wires 118, 119 and 120 and switch 121, 115 switch 121 being normally closed. While I have indicated a battery as the source of current, it is obvious that the engine dynamo could supply the necessary current. It will be seen that when the engine tender passes over the roadbed switch, it will attract the paddle end of lever 110, causing contact lever 110 to make contact with contact point 112 completing the relay circuit and causing the crossing protector to operate. 120 125

The circuit of the electromagnet 115 is normally closed, but if the engineer does not wish to close a crossing which he is approaching, he may operate switch 121 to break the circuit, causing electromagnet 115 130

to be de-energized. The electromagnet will then pass over the roadbed switch without operating the same. The electromagnet may be carried by any part of the train equipment and be operated by any desired operator. Instead of using an electromagnet, a permanent magnet may be used.

The operation is as follows: With the crossing protectors in open position, allowing traffic along the highway to pass over the tracks (as shown in Fig. 1), a train approaching the crossing from either direction will pass over one of the roadbed switches 19 mounted on a crosstie in the center of the track a predetermined distance from the crossing. The magnet 115 carried by the train will attract contact lever 110 causing it to close the relay circuit. Current will flow from battery 57 through conductor 59, normally closed switch 61, conductor 66, main relay coil *a*, conductors 18, 16, 14, roadbed switch 19, and conductors 13, 15 and 17. Energizing of relay coil *a* will cause relay armature 64 to close the motor circuit. The current flows from battery 57 through conductor 59, normally closed switch 61 and conductor 60 to one terminal of the motor 38, the other motor terminal being connected by conductor 62, armature 64 (now closing the circuit between contacts 64^a and 64^b) and conductor 63 to the other terminal of the battery. At the same time that the motor circuit is closed a shunt circuit through relay coil *b* is established. One terminal of coil *b* is connected by conductor 67 to conductor 62 of the motor circuit and the other terminal is connected by conductor 67^a to armature 64 which connects with conductor 63 of the motor circuit. This auxiliary or holding relay coil *b* is provided to maintain armature or switch member 64 in closed position for a predetermined time, i. e. long enough to allow the motor to finish the winding operation. Roadbed switch 19 is only closed momentarily as the train passes over the same so that relay coil *a* would only be energized for an instant, consequently armature or switch member 64 would only close the motor circuit momentarily unless some means as described above were provided to maintain the armature or switch member 64 in closed position long enough to allow the motor to complete the winding operation.

55 The motor now begins to turn, rotation of motor shaft 39 being transmitted through gearing 43, 44 and 45 to bowl or crown gear 48 which in turn is rigidly connected to ratchet disk 35. Ratchet disk 35 is mounted on gate shaft 22 in such a way as to permit rotation of ratchet disk 35 relative to shaft 22 while preventing relative longitudinal movement of the disk and shaft. One end of spring 33 is connected to disk 35, the other end being connected to collar

34 rigidly connected to shaft 22 so that rotation of the motor winds the spring which in turn tends to rotate shaft 22, but rotation of shaft 22 is prevented by plunger 49 engaging in one of the recesses 52 in the 70 arms casting or block 24. The motor, however, continues the winding operation until one of the pins 56 in bowl gear 48 strikes the trip 53. This reciprocates connecting link 55 causing pin 55^a, carried by the link, 75 to open switch 61 breaking the motor circuit and also the auxiliary or holding relay circuit. At the same time plunger 49 is withdrawn from one of the recesses 52 to permit the gate shaft 22 and the gate arms 80 carried thereby to swing. The speed of turning is regulated by governor 68 connected to gate shaft 22 by gearing 69, 70, 71, 72, 73 and 74. While the gate is turning, the gong 85 is sounded by mechanism 85 operated by gear 70 forming a part of the governor operating gearing. Rotation of gate shaft 22 and the gate arms carried thereby will continue until plunger 49 engages in the next recess in arms casting 24 90 which occurs when the gate arms are thrown across the highway.

The roadbed switches 19 are placed at such distances from the crossing that by, or just before, the time the train reaches the 95 crossing, the protectors have closed the highway. If the train continues in the same direction, the roadbed switch on the other side of the crossing will be operated and the operations described above will be repeated to swing the gates to open position. If instead of continuing in the same direction, the train were to stop at the crossing and return in the direction from which it came, the same roadbed switch which had 105 been operated to swing the gates to closed position would again be operated to open the gates.

If, for any reason, the electric motor 38 will not operate, the gates can be operated by turning motor shaft 39 manually by means of a hand crank 42. When a gate or protector is first placed into operation, it is desirable to place the spring 33 under a certain amount of tension and the hand- 110 crank 42 can be used for this purpose.

Various changes in the construction and arrangement of the parts of the mechanism may be made without departing from the spirit or scope of the invention as specified 120 in the claims.

What I claim is:

1. A crossing protector comprising a gate, means for yieldingly opening and closing said gate, means for energizing said opening and closing means, and means for setting into operation and discontinuing the operation of the energizing means.

2. A crossing protector comprising a gate, resilient means for opening and closing said 330

- gate, means for placing said resilient means under tension, and means for setting into operation and discontinuing the operation of the means for placing the resilient means under tension.
3. A crossing protector comprising a gate, spring means for opening and closing said gate, means for winding said spring means, and means for setting into operation and discontinuing the operation of said winding means.
4. A crossing protector comprising a gate, means for opening and closing said gate, means for energizing said opening and closing means, means for setting said energizing means into operation, and means operated by said energizing means for throwing said energizing means out of operation.
5. A crossing protector comprising a gate, means for operating said gate, means for locking said gate against operation, means for energizing said operating means, means for setting said energizing means into operation, and means operated by said energizing means for throwing said energizing means out of operation and for releasing the gate locking means.
6. A crossing protector comprising a gate, means for locking said gate against operation, a motor, resilient means connecting said gate and said motor, said resilient means adapted to receive and store energy from said motor, means for setting the motor into operation, and means for throwing the motor out of operation and for releasing the gate.
7. A crossing protector comprising a gate, spring means for opening and closing said gate, means for locking said gate against operation, means for winding said spring means, means controlled by movements of a vehicle for connecting said winding means with a source of power, and means for automatically disconnecting the winding means from the power source after a predetermined operation of said winding means and for releasing said gate locking means.
8. A crossing protector comprising a gate, spring means for operating said gate, means for locking said gate against operation, a motor for winding said spring means, a source of power, means including a switch operated by movements of a vehicle for connecting said motor with said source of power, and means actuated by said motor for disconnecting said motor from the power source and for releasing said gate locking means.
9. A crossing protector comprising a gate, resilient means normally tending to operate said gate, means for normally locking said gate against operation, and means controlled by the movement of a train for releasing said gate-locking means.
10. A crossing protector comprising a gate, spring means normally tending to op-
- erate said gate, means for locking said gate against operation, means for winding said spring means, means for setting said winding means into operation, and means actuated by said winding means for throwing said winding means out of operation and for releasing said gate-locking means.
11. A crossing protector comprising a gate, spring means for operating said gate, means for locking said gate against operation, a motor for winding said spring means, means for connecting said motor with a source of power, means for maintaining the connection of the motor with a source of power, and means operated by the motor for disconnecting the motor from the power source and for releasing the gate locking means.
12. A crossing protector comprising a gate movable in one direction to open and closed positions, operating means, and means for resiliently connecting said operating means and said gate.
13. A crossing protector comprising a gate, resilient means for opening and closing said gate, a motor for winding said resilient means, a relay, a power circuit opened and closed by said relay, and means controlled by movements of a train for operating said relay.
14. A crossing protector comprising a gate movable in one direction to open and closed positions, resilient means for operating said gate, means for automatically connecting said operating means to a source of power, and means operated by the operating means for disconnecting the operating means from said power source.
15. A crossing protector comprising a casing, a vertical shaft mounted for rotation in one direction only in said casing, gate arms carried by said shaft, spring means for rotating said shaft, means for winding said spring means, means controlled by movements of a vehicle for connecting said winding means with a source of power, and means for automatically disconnecting the winding means from the power source after a predetermined operation of said winding means.
16. A crossing protector comprising a casing, a vertical shaft mounted for rotation in one direction only in said casing, gate arms carried by said shaft, spring means for rotating said shaft, a motor for winding said spring means, a relay, a power circuit controlled by said relay for connecting said motor with a source of power, means for energizing said relay, and means operated by said winding means for disconnecting the winding means from the power source after a predetermined operation of said winding means.
17. A crossing protector comprising a casing, a vertical shaft supported for rotation

- in said casing, gate arms carried by said shaft, means for locking said shaft against rotation, spring means connected to said shaft, means for winding said spring means, 5 means for setting said winding means into operation, and means actuated by said winding means for throwing said winding means out of operation and for releasing said locking means.
- 10 18. A crossing protector comprising a casing, a vertical shaft supported for rotation in said casing, gate arms carried by said shaft, means for normally locking said shaft against rotation, spring means connected to said shaft, a motor for winding said spring means, a source of power, means for connecting said motor with said source of power, means for disconnecting said motor from the power source after a predetermined operation of the motor and for releasing said locking means.
- 15 19. A crossing protector comprising a casing, a vertical shaft supported for rotation in said casing, gate arms carried by said shaft, means for locking said shaft against rotation, spring means connected to said shaft, a motor for winding said spring means, a source of power, a relay for connecting said motor with the power source, 20 means controlled by movement of a train for energizing said relay, means for disconnecting said motor from said power source after a predetermined operation of the motor, and means for releasing said locking means.
- 25 20. A crossing protector comprising a casing, a vertical shaft supported for rotation in said casing, gate arms carried by said shaft, a member secured to said shaft and 40 provided with a series of recesses, a bolt mounted on said casing normally engaging in one of said recesses to hold the shaft against rotation, spring means connected to said shaft, a motor for winding said spring means, a source of power, means for connecting said motor with the source of power, 45 means for controlling the operation of the connecting means, means for disconnecting said motor from said power source after a predetermined operation of the motor, and means for withdrawing said bolt from one of said recesses to permit rotation of said shaft.
- 50 21. A crossing protector comprising a casing, a vertical shaft supported for rotation in said casing, gate arms carried by said shaft, a member secured to said shaft and 55 provided with a series of recesses, a bolt mounted on said casing normally extending into one of said recesses to hold said shaft against rotation, spring means connected to said shaft, means including a motor and a gear member provided with projections for winding said spring means, a source of power,
- means for connecting said motor with the source of power, means controlled by movements of a train for controlling the operation of the connecting means, a trip lever, 65 said trip lever operated by engagement of one of the projections on said gear member after a predetermined operation thereof to disconnect said motor from the source of power and to withdraw said bolt from said recess to permit the gate shaft to rotate.
- 70 22. A crossing protector comprising a gate, spring means normally tending to operate said gate, means for locking said gate against rotation, means for winding said spring means, means for setting said winding means into operation, means 80 operated by said winding means for throwing said winding means out of operation after a predetermined operation thereof, and means for releasing said locking means, to permit rotation of said gate, said locking means automatically locking the gate against rotation after a predetermined rotation of the gate.
- 85 23. A crossing protector comprising a rotatable gate, spring means for operating said gate, means for winding said spring means, means for controlling the operation of said winding means, and means for regulating the speed of rotation of said gate.
- 90 24. A crossing protector comprising a rotatable gate, spring means for operating said gate, means for winding said spring means, means for controlling the operation of said winding means, and means operated by said gate for giving an alarm while the 100 gate is rotated.
- 95 25. A crossing protector comprising a rotatable gate, spring means for operating said gate, means for winding said spring means, means for controlling the operation 105 of said winding means, speed control means, alarm-sounding means, and means including a clutch for connecting said speed control means and said alarm-sounding means to said gate, said clutch disconnecting said 110 gate from said speed control means and said alarm-sounding means when rotation of said gate is suddenly stopped.
- 115 26. A crossing protector comprising a gate, spring means for operating said gate, electrically operated means for winding said spring means, auxiliary manually operated means for winding said spring means, and means for controlling the operation of said 120 electrically operated winding means.
- 125 27. A crossing protector comprising a rotatable gate, spring means for operating said gate, means for winding said spring means, said gate remaining stationary during the winding operation, and means for controlling the operation of said winding means.
28. A crossing protector comprising a

rotatable gate; means for operating said gate, means for locking said gate against operation, means for energizing said operating means, means for setting said energizing means into operation, means operated by said energizing means for throwing said energizing means out of operation and for

releasing the gate locking means, and means for regulating the speed of rotation of said gate.

10

In testimony whereof I hereunto affix my signature.

ANDREW J. BAKER.
